SWEETENING PETROLEUM OILS

John Happel, Jr., Brooklyn, and Donald Warren Robertson, Queens Village, N. Y., assignors to Socony-Vacuum Oil Company, Incorporated, New York, N. Y., a corporation of New York

No Drawing. Application November 13, 1939,
Serial No. 304,205

4 Claims. (Cl. 196—30)

This invention has to do with processes for the treatment of straight run and cracked gasolines, naphthas, kerosenes and similar light petroleum products for the purposes of rendering those products sweet to the doctor test. These products as originally produced usually contain a sufficient amount of the so-called "sour" sulphur compounds usually of the nature of mercaptans and related compounds to cause the products to be objectionable for the purposes of commerce. The products are consequently treated in some manner either to remove the sour sulphur compounds or to alter them to forms such as disulphides which are not objectionable in a finished product.

The most widely used sweetening process is that which is commonly known as "doctor" treatment, in which gasoline, naphtha or kerosene is contacted with an excess of aqueous alkaline solution of sodium plumbite and with a measured amount of sulphur. The reactions of sweetening are believed to take place substantially in accordance with the following equations:

While quite generally utilized, this doctor process is not entirely satisfactory for a number of reasons and considerable activity in research is directed towards search for improvement of the process, or to other processes capable of accomplishing the same general objects. One of the drawbacks of the doctor process is the formation of emulsions with the aqueous reagents which result in product losses and necessitate increased settling equipment. This tendency to emulsify is more pronounced in cracked stocks than in straight run products and at low temperatures more than at elevated temperatures.

Another drawback of the doctor process arises from the necessity of having an excess of alkalinity in the treating reagent giving rise to a treated product sometimes having relatively high alkalinity. If the free alkali is not thoroughly removed from the treated product, it seriously interferes with the action of the inhibitors commonly added to gasolines for improving their storage stability.

Among the processes that have been proposed for accomplishing this object of sweetening, there are such processes as the dry sweetening processes which employ solid reagents, such as lead sulfide and cupric chloride, deposited on granular inert carriers, the oil being percolated through a bed of the contact mass in the presence of dissolved oxygen or sulphur. These processes obviate many

of the difficulties arising from the use of aqueous alkaline solutions but still are at a common disadvantage with the conventional processes in that they involve costly handling of considerable quantities of reagents.

Related wet processes employing copper and similar reagents have likewise been proposed, but these processes are usually either inapplicable to many of the products which must be sweetened or present difficulties in the way of control of side reactions which renders them less attractive than the usual doctor operation.

Since many of the difficulties of the usual systems of operation revolve around the carrying of the reagent utilized in large volumes of aqueous solution, there have been proposed some processes wherein oil soluble reagents have been utilized and a minor use of aqueous treating solutions made. For example, copper naphthenate is highly oil soluble and undergoes double decomposition with mercaptides in oil solution to form copper mercaptides which are not oil soluble and which may be removed readily from the oil, after which a light caustic wash will serve to free the oil of the naphthenic acid without encountering the usual emulsion difficulties and without requiring the utilization of large volumes of aqueous alkaline treating reagent. This method, however, is not highly applicable since some of the naphthenates most convenient for such use are those in which the metal radical does not form mercaptides which are sufficiently insoluble in oil to bring about their ready and complete removal.

This invention has for its object the provision of a method for the sweetening of oils under controlled conditions in the absence of aqueous alkaline sweetening reagents capable of effecting a complete quantitative ready removal of the objectionable products of reaction from the oil treated. It has as a further object the provision of a method of sweetening utilizing as main reagents products which are entirely oil soluble and which consequently may be added to the reaction in precisely controlled proportions as solutions in an oil of the same nature as the oil to be treated. A further object is the provision of a process capable of utilizing a lesser amount of certain of these reagents than any process heretofore taught. These, and further objects, such as will be made apparent by consideration of this specification may be attained by practice of the process herein described.

The present invention accomplishes the several objects outlined by carrying out the usual sweetening reaction, that is, the conversion of mer-

captans to disulfides, by treating the sour oil with controlled amounts of oil solutions of lead soaps and sulphur, followed by settling and removal of the lead sulfide and by removal of the acid as for example by use of lead naphthenate. In this manner the usual sweetening reaction is carried out entirely in the oil phase, thus eliminating any possibility of emulsion losses and greatly minimizing the possibility of residual alkalinity in the treating stocks. Very small amounts of lead naphthenate and sulphur are required, and since these may be added to the process in the form of solutions in oil, having easily determinable and easily controlled concentrations, extremely precise control of the amount of reagents utilized can be had when conducting the plant operations in any conventional continuous sweetening apparatus, merely by the establishment of proper proportions between the flowing streams of oil to be treated and of the oil solutions of the two reagents. There is no necessity for utilizing complicated systems for preparing reagents, since the reagents indicated are quite readily soluble in oils of the nature of those to be treated, at least to an extent entirely sufficient for the purposes of the present reaction. The process may, in fact, be substantially self contained in that the oil used as a carrier for the reagents conveniently and indeed preferably, may be a portion of the oil which has already been through the sweetening operation. The process is entirely acceptable in results since the sweetened product in addition to being sweet to the doctor test (U. S. Gov. Test 520.31), is also non-corrosive (ASTM Method D 130-30), and does not require re-running.

While the exact mechanism of the reaction taking place is not entirely clear, it is quite evident that the overall result obtained conforms substantially to the usual doctor sweetening reaction, except that an organic acid, e. g., naphthenic acid, takes the place of the usual sodium hydroxide, as may be seen from the following equations:

The result of the reaction is the production from an alkyl mercaptide and a lead compound of an alkyl disulfide and lead sulfide. The reaction in many ways is quite similar to that of doctor sweetening in that upon the addition of the lead naphthenate solution to the oil, there is not produced a precipitate which may be removed from the oil and that the reaction is not completed except in the presence of or until the addition of free sulphur. Just as in the usual doctor sweetening process, it is necessary to add sulphur to get a "break." Experience has shown that in the case of sour oils, an immediate break is gotten upon the addition of free sulphur, whereas, in the absence of such sulphur, the reaction which has at that time proceeded only so far as the production of a lead mercaptide, has not resulted in the formation of any reaction product which can be removed from the oil by any process conveniently and commercially available or which may be allowed to remain in the oil, if the oil is to be marketed.

A further difference over processes presently proposed exists in the fact that instead of requiring the utilization of the amount of lead naphthenate normally equivalent to the mercaptan present in the oil to be treated, it has been established that only from 30% to 50% of the calculated amount of lead is necessary. It consequently appears that there is in this reaction some-

thing more than the plain steps indicated by the above equations, in that lead compounds in the presence of sulphur appear to exhibit a catalytic effect on a conversion of mercaptans into disulfides. Furthermore, it has been found that within these limits, that is, with amounts of lead less than the theoretical, according to the above equations, it is quite necessary that the amount of lead which is added in the form of a lead soap solution, in order to give a break or precipitation of lead sulfide, should be controlled within quite close limits. These limits can readily be determined for each lot of sour oil by simple laboratory tests. The amount of sulphur which is utilized, while it should be controlled so that no excess of sulphur remains in the oil to cause a positive copper strip corrosion test, need not be given such close attention as should the amount of lead.

Among the usual refinery stocks, the cracked products and particularly those containing the higher mercaptans, are more difficult to sweeten. In demonstrating the capability of the novel sweetening process herein disclosed, tests were conducted upon that heavy part of cracked gasoline line boiling between 200° F. and 400° F., known to the industry as "debutanizer bottoms," that stock being known as one of the normally more difficult stocks usual in refinery practice.

The sweetening operations were conducted by mixing the sour oil with sulphur solution and then with various amounts of lead naphthenate solution as shown below. The sulphur solution was prepared by dissolving 0.4% of sulphur in a portion of the sour oil, and the theoretical amount of sulphur, one part for every two parts of mercaptan sulphur in the sour oil, was added. The lead naphthenate was prepared in naphtha solution (300° F. to 400° F. boiling range) containing 39 grams of Pb per liter.

EXAMPLE 1

Debutanizer bottoms—mercaptan S content 0.15 grm./liter, S added (in solution) 0.072 grm./liter

Vol. percent Pb naphth. solution added	Pb added, percent of theoretical	Merc. S content of treated product, grms./liter	Doctor test	Break
0	0	.15	Positive.....	None.
0.1	7	.08	do.....	Quick.
0.2	15	.05	do.....	Do.
0.3	23	.03	do.....	Do.
0.4	31	0	Negative.....	Do.
0.5	38	0	do.....	None.
1.3	100	0	do.....	Do.

EXAMPLE 2

Debutanizer bottoms—mercaptan S content 0.17 grm./liter, S added (in solution) 0.08 grm./liter

Vol. percent Pb naphth. solution added	Pb added, percent of theoretical	Merc. S content of treated product, grms./liter	Doctor test	Break
0	0	.17	Positive.....	None.
0.5	36	.05	do.....	Quick.
0.6	43	.03	do.....	Do.
0.7	50	0	Negative.....	Do.
0.8	57	0	do.....	None.
1.4	100	0	do.....	Do.

All sweetened products passed the copper strip corrosion test.

It will be noted that both the negative doctor test and the quick break were obtained simultaneously when the amount of lead added was proper-

ly controlled. In Example 1 this corresponded to 31% of the lead theoretically required according to the equations, and in Example 2, to 50%.

Free sulphur and lead naphthenate do not react in the absence of mercaptans, e. g., no darkening or break occurs when lead naphthenate is added to a sweet naphtha containing an adequate amount of free sulphur, but the subsequent addition of mercaptan produces the precipitate of lead sulfide.

It will also be noted that with larger amounts of lead reagent than the optimum, that no break is gotten, although in many such cases a break can be obtained by the addition or with the assistance of an absorbent, such as clay, which, however, introduces a new operating step which in itself may be objectionable.

While the most convenient and preferred form of lead soap to be used is lead naphthenate, any oil soluble lead soap may be used in this sweetening procedure. The lead naphthenate is preferred, because of its high solubility in petroleum fractions of the nature of those to be treated, because it is readily available and may be produced locally as a by-product of the usual operations of refining. The amount of lead utilized in the form of lead soap for the proper conduct of this sweetening process will, of course, vary somewhat with the nature of the oil to be treated, but it will be found in the usual instance to be between from about 20% to about 65% of the theoretical amount of lead required, based upon the mercaptan sulphur content of the oil being treated and will in all cases be substantially less than the theoretical amount required for double decomposition between the lead soap reagent and the mercaptan present.

In many cases, the presence of organic acidic residues in the treated products resulting from the sweetening reaction will not be objectionable. However, in case it is desired to remove them, either for the benefit of the product or to permit their recovery for further utilization by return to the process, all that is necessary is the subjection of the treated product to a very light alkaline wash in which very little difficulty with emulsions and with residual alkalinity of the treated oil will be experienced.

We claim:

1. The method of rendering oil fractions con- 50

taining sour sulphur compounds sweet to the doctor test which comprises contacting the oil to be treated with an oil soluble lead naphthenate and with added reagent sulphur in the absence of water, and at normal atmospheric temperature, and removing from the oil the lead sulfide formed by the reaction.

2. The process of rendering oil fractions containing sour sulphur sweet to the doctor test without the use of aqueous solutions, which comprises admixing with the oil a quantity of an oil soluble lead naphthenate substantially less than that theoretically required to effect double decomposition with the sour sulphur compounds present and also introducing to the reaction a quantity of free sulphur sufficient to cause the precipitation of lead sulfide and separating from the oil the lead sulfide so produced.

3. The method of rendering oil containing sour sulphur compounds such as mercaptans sweet to the doctor test without the use of aqueous solutions, which comprises admixing with the oil to be treated a controlled amount of an oil solution of an oil soluble lead naphthenate and a controlled amount of free sulphur, the amount of lead so utilized being from about 20% to about 65% of that theoretically required for double decomposition with the mercaptans present, and remove from the oil the lead sulfide formed by the reaction.

4. The process of treating sour petroleum distillates containing mercaptans to convert said mercaptans to disulfides, thereby rendering the oil sweet to the doctor test without the use of aqueous solutions, which comprises admixing with the oil a quantity of an oil soluble lead naphthenate, which quantity of lead naphthenate contains between about 20% and about 65% of the lead theoretically necessary for double decomposition with the mercaptans present and a quantity of free sulphur, the lead and sulphur so introduced being so proportioned with respect to the mercaptan sulphur present in the oil to be treated that a quick break is obtained in the treating and that lead sulfide may be precipitated and removed without substantial increase in the amount of sulphur in the oil treated.
